F. BILLINGS

PROTECTOR CAP FOR GAS TANKS

Filed Dec. 13, 1923

UNITED STATES PATENT OFFICE.

FREDERICK BILLINGS, OF WEST ALLIS, WISCONSIN.

PROTECTOR CAP FOR GAS TANKS.

Application filed December 13, 1923. Serial No. 680,440.

To all whom it may concern:

Be it known that I, FREDERICK BILLINGS, a citizen of the United States, and resident of West Allis, in the county of Milwaukee and State of Wisconsin, have invented certain new and useful Improvements in Protector Caps for Gas Tanks; and I do hereby declare that the following is a full, clear, and exact description thereof.

10 This invention relates to protector caps for gas tanks.

Objects of this invention are to provide a protector cap for a gas tank which may be permanently left in place, which permits 15 the use of the tank without altering or removing the cap and which will fully and adequately protect the valve of the tank from damage during shipment.

Further objects are to provide a protector 20 cap for a gas tank which may be readily applied to the tank, which may be produced with a minimum of machine work, and which will be securely retained in position.

Embodiments of the invention are shown 25 in the accompanying drawings, in which:—

Figure 1 is a view of the gas tank with the cap applied,—the cap being shown in section, such view corresponding to a section on the line 1—1 of Figure 3.

30 Figure 2 is a front view of the structure shown in Figure 1.

Figure 3 is a plan view of the cap in position, such view being partly in section.

Figure 4 is a view of a modified form of 35 the invention.

The portable gas tank 1 is provided with a neck 2 which, at its upper end, terminates in an outward projecting collar 3 spaced from the body of the tank. This neck portion 40 is internally threaded and receives the downwardly extending portion 4 of the valve 5, such valve being provided with a laterally extending threaded member 6. At the upper end of the valve, a short valve 45 stem 7, equipped with a square portion 8 is provided,—this squared portion being adapted to receive the socketed portion of a removable valve wrench or valve stem.

The protector cap comprises a front half 50 section 9 and a rear half section 10, each provided with inwardly directed flanges 11 which are adapted to be fitted beneath the flange 3 of the tank. These members are provided with apertures certain of which 55 are threaded, adapted to receive screws 12

whereby the two half sections may be held together in place upon the tank.

The front member 9 is provided with an aperture 13 which provides access to the threaded fitting 6 of the valve. The top of 60 each of the sections is equipped with a semi-circular cutout which, together, form a circular recess 14 (see Figure 1) adapted to permit the entrance of the wrench or removable valve stem through the cap.

In the modified form shown in Figure 4, the aperture 13' in the protector cap, which corresponds to the aperture 13 in the first form is internally threaded. This threaded aperture is adapted to be closed by a removable screw threaded plug 15 to further protect the valve, particularly during shipping. Obviously, if desired, the upper opening 14' 65 could also be threaded and provided with a removable screw threaded plug in a manner similar to that provided for the opening 13'.

It is to be particularly noted that this cap may be permanently left in place on the tank and that the tank may be used in its usual capacity without alteration or removal 70 of the cap. The opening 13 provides sufficient space for the easy insertion of the connecting portion of the discharge pipe and the opening 14 permits the ready entrance of the socketed removal valve stem.

It will be seen that a protector cap for 75 gas tanks has been provided which may be most readily produced, which is of sturdy and substantial construction, which may be permanently positioned upon the tank in a simple and easy manner and which provides the necessary freedom for the manipulation of the valve.

Although one form of the invention has 80 been described in considerable detail, it is to be understood that the invention may be variously embodied and is, therefore, to be limited only as claimed.

I claim:

1. In a device of the class described, a 85 gas tank having an internally threaded upwardly extending neck terminating in an upper outwardly projecting flange, a valve screwed into said neck and having a laterally extending delivery portion and an upper valve stem, a protector cap comprising a hollow body portion surrounding said valve and having a front opening giving access to said laterally extending portion, and an upper opening giving access to said valve 90

stem, said protector cap being formed of two half sections each having inturned flanges adapted to be positioned beneath the upper flanges of said neck, and securing 5 means for holding said half sections together.

2. The combination of a gas tank provided with an internally threaded upwardly extending neck having an upper outwardly 10 extending flange spaced from the body portion of the tank, a valve having a downwardly extending threaded portion screwed into said neck and, having a laterally extending delivery portion and having an upper valve stem, and a protector cap having 15

a body portion surrounding said valve and provided with an upper opening giving access to said valve stem, a front opening giving access to said laterally extending portion of said valve, said protector cap having an inturned lower flange positioned beneath the upper flange of said neck, said front opening being threaded, and a threaded removable member temporarily closing said front opening. 20 25

In testimony that I claim the foregoing I have hereunto set my hand at Milwaukee, in the county of Milwaukee and State of Wisconsin.

FREDERICK BILLINGS.
